UNITED STATES PATENT OFFICE.

CECIL E. BRYAN, OF CHICAGO, ILLINOIS.

MAUSOLEUM.

1,083,660.

Specification of Letters Patent. Patented Jan. 6, 1914.

Application filed August 27, 1913. Serial No. 786,862.

To all whom it may concern:

Be it known that I, CECIL E. BRYAN, a citizen of the United States, residing at Chicago, in the county of Cook and State of Illinois, have invented certain new and useful Improvements in Mausoleums, of which the following is a specification.

This invention relates more particularly to a combined ventilating and disinfecting apparatus for the crypts of mausoleums.

Among the objects of this invention are to provide means whereby each crypt may be provided with a suitable outlet for gases, such outlet being preferably through a liquid seal in which the liquid consists of some disinfecting or de-odorizing solution or compound; to provide means whereby a plurality of crypts may be vented through a common outlet pipe or system of pipes; to provide means whereby one or more of a plurality of connected outlet devices for different crypts may be closed and then opened as the crypts are put into use; and in general to provide such an improved ventilating and disinfecting system as will appear more fully from the following specification.

In the accompanying drawings illustrating this invention; Figure 1 is a sectional view of a mausoleum showing the crypts provided with my improved system; Fig. 2 is a detail of one of the disinfectant receptacles or seals with which each crypt is supplied; and, Fig. 3 is a detail showing a modified form of the receptacle or seal.

As indicated in Fig. 1, 4, 4, represent a plurality of super-imposed crypts as ordinarily arranged in a mausoleum, each crypt is provided with a receptacle or liquid seal 5, such as indicated in Fig. 2 for receiving any suitable disinfecting or de-odorizing liquid, such as formaldehyde or other suitable material. These receptacles are preferably embedded in the side walls of the crypts, as indicated in Figs. 1 and 3, and are provided with inlet pipes 6, which extend into the inner portion of the crypt. These pipes are connected to the bottoms of the receptacles 5 and, in the form shown in Figs. 1 and 2, their upper ends are left open, these ends terminating adjacent to the top of the receptacles. The top of the receptacle 5 is provided with an upwardly

extending pipe 7, which connects with branch pipes 8 and 9. The pipe 8 leads to 55 a convenient point within the building for pouring in liquid and is provided with a cap or closure 10. The pipe 9 leads to any suitable place for permitting the escape of gases. A plurality of these pipes may for 60 instance be connected to a common pipe 11 leading to the outer atmosphere. The lower end of the pipe 7 connects with a substantially horizontal pipe 12, as by means of a T 13. One branch or end 14 of the pipe 12 65 terminates within the casing or receptacle 5 and is provided with a valve 15 having its stem 16 passing out through the casing and into the inner area of the crypt so that the valve may be operated from within the 70 crypt. The other branch or end 17 of the pipe 12 extends out through the side of the receptacle 5 where it connects with a pipe 18, which pipe leads down and connects with a pipe 12 of the next lower receptacle 5, these connections being continued down to the bottom of the series. The end 17 of the pipe 12 of the lowermost receptacle is connected with an overflow or 80 indicator pipe 19, which leads to a convenient point at the bottom of the mausoleum where it is provided with a cap or closure 20. It will be understood that all of the connections of the pipe with the receptacle 5 or where they pass through the same are 85 substantially air-tight, and such receptacle may be made in any desired manner.

The operation of the device is as follows: Assuming that all of the valves 15 are closed in the first instance, and one or more bodies 90 are placed in any of the crypts of a vertical series, then the valves 15 in such crypts are opened and a sufficient amount of formaldehyde or suitable fluid is poured in through the pipe 8 to substantially fill the receptacles 95 5 in which the valves have been opened. The pipes 12 are preferably given a slight pitch so that the ends 14 are a little lower than the ends 17, but not sufficiently lower so that the liquid in the receptacle would seal the open 100 end 14. The liquid then running down the pipe 7 will pass out through the open end 14 until the top receptacle 5 is filled to a level approximately co-inciding with the bottom of the opening through the pipe 12. The 105 liquid then overflows through the pipe 12

and down the pipe 18, and then passes into the next receptacle if the valve 15 thereof is open. If such valve is not open it then passes down until it comes to a receptacle 5 having such valve open and when all of the receptacles with their valves open have been filled, the overflow will run down through the pipe 19, where it may be observed by having the cap 20 removed and the attendant 10 will then be aware that all of the proper receptacles have been filled. The cap 20 is then replaced. With the valve 15 open and the receptacle filled with liquid up to the pipe 12, or approximately thereto, it will be 15 noted that there is a free outlet passageway through the connected pipes 7, 12 and 18, from any of the receptacles. If any gases are formed in any of the crypts thus provided, which crypts are sealed so that they 20 are substantially air-tight, they will be permitted to escape down through the pipe 6, then through the liquid in the receptacle 5 and out through the pipes 7, 9 and 11 from the top receptacle or out through such pipes 25 and the pipes 12 and 18 from any lower receptacle. It is assumed, of course, that the pressure of the gas in the crypt will be sufficient to force the same out through such liquid seal, but the depth of the seal may be 30 regulated by the location of the connection from the lower end of the pipe 6. It will also be noted that the pipe 6 being partially filled with the disinfecting liquid, a certain amount thereof may evaporate and escape 35 into the crypts.

From the foregoing description it will be seen that the crypts are provided with a common outlet which consists in this particular instance, of the series of pipes 18 40 leading from one crypt to another, the pipe 7, the connecting pipes 12, and the necessary fittings for the various connections. This common outlet is connected with the various crypts by the open pipe ends 14, such openings being controlled both by the valves 15 and by the liquid seals, as above described.

By means of this arrangement it will be readily seen that I provide a simple and efficient apparatus whereby any one or more crypts may be vented, and whereby the gases passing from such crypts will be passed through a disinfecting or de-odorizing liquid before being allowed to escape in the atmosphere. Such solution may also be replenished at any time by again pouring liquid in through the pipe 8 until it fills the receptacles in which the valves have been opened, in the manner above described.

In the slightly modified form of device 60 shown in Fig. 3, the receptacle 5 is provided with substantially the same pipe connections as above described, but the valve is omitted from the end of the pipe 12. The pipe 6 is provided with a plug 21 at its upper end

and when one of the crypts is to be used, 65 such plug is removed and liquid poured in through the open end of this pipe until a desired amount is placed in the receptacle. If no liquid is intended to escape through the pipe 12, the upper end of the pipe 21 may 70 be below such pipe, for instance at a point indicated at *a*, so that the attendant cannot fill the receptacle to a point above the upper end of this pipe. If desired, an additional liquid inlet pipe 22 may be connected with 75 the receptacle 5 and extended out beyond the front wall of the crypt so that additional liquid may be supplied to the receptacle after the crypt has been sealed. In such case the pipe 22 is provided with a plug or closure 80 85 at its outer end for closing the same.

It will be observed that other changes in the details of construction may suggest themselves, which will come within the spirit of this invention, and therefore, I do not 85 wish to limit myself to the exact construction or arrangement herein shown and described, except as specified in the appended claims, in which I claim:

1. In a mausoleum, the combination of a 90 plurality of crypts, a common outlet from said crypts having openings into each crypt, valves for said openings, liquid seals interposed between said openings and the crypts, and means for supplying liquid to said seals 95 through said common outlet.

2. A ventilating apparatus for mausoleums, comprising the combination with a plurality of super-imposed crypts, of receptacles for each crypt having pipes leading from the bottoms thereof, upwardly with their upper ends opening into the crypts, substantially horizontal pipes in the upper ends of said receptacles, one end of each of said pipes extending out through the wall 100 of the receptacle, and the other end opening in the receptacle, valves for said open ends, pipes leading upwardly from said horizontal pipes, the upwardly extending pipe from the top receptacle leading to a suitable point 110 for discharging gases and also having means for pouring liquid therein, the upwardly extending pipe from the other receptacles being connected with the outer ends of the horizontal pipes of the next receptacles and 115 an overflow or observation outlet pipe from the horizontal pipe of the lowermost receptacle, the arrangement being such that when a valve in any receptacle is opened and liquid poured in from the top pipe, it will fill said receptacle until the liquid overflows through the horizontal pipe, such receptacles then 120 furnishing means whereby gases may escape through the connected pipes to the outer atmosphere.

3. In an apparatus of the character set forth, the combination with a plurality of super-imposed crypts, of connected pipes

for forming a common outlet conduit, openings from said pipes leading to the respective crypts, receptacles for inclosing each of said openings, vent pipes from the crypts leading to points adjacent to the bottoms of said receptacles, means for supplying disinfecting liquid to said receptacles, and means

for closing communication from the crypts through said receptacles and outlet pipes.
